US0D1083413S

(12) **United States Design Patent** (10) **Patent No.:** **US D1,083,413 S**
(45) **Date of Patent:** **** Jul. 15, 2025**

(54) **STEP STOOL**

(71) Applicant: **Mark Raymond Stultz**, Maple Grove, MN (US)

(72) Inventor: **Mark Raymond Stultz**, Maple Grove, MN (US)

(**) Term: **15 Years**

(21) Appl. No.: **29/899,075**

(22) Filed: **Aug. 4, 2023**

Related U.S. Application Data

(63) Continuation-in-part of application No. 17/667,771, filed on Feb. 9, 2022, now Pat. No. 12,075,910.

(57) **CLAIM**

The ornamental design for a step stool as shown and described.

DESCRIPTION

FIG. 1 is a perspective view of a first embodiment of a step stool showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a perspective view of a second embodiment of a step stool showing my new design;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

The broken lines in the figures are included for the purpose of illustrating portions of a step stool and form no part of the claimed design.

1 Claim, 14 Drawing Sheets
